MACHINE FOR COMBINING AND WINDING
TWO OR MORE WEBS OF FLEXIBLE MA-
TERIALRobert McC. Johnstone, Short Hills, N. J., as-
signor to Cameron Machine Company, Brook-
lyn, N. Y., a corporation of New York

Application May 8, 1935, Serial No. 20,365

2 Claims. (Cl. 154—42)

This invention relates to a method of and means for combining and winding two or more webs of flexible material and has for its main object and feature the combining of two webs 5 that are being wound in overlapped relation.

In the accompanying drawings the invention is shown in a concrete and preferred form in which:

Fig. 1 is a view in end elevation, with parts 10 broken away and in section but looking generally in the direction of arrows 1—1 of Fig. 2, of a machine embodying the invention;

Fig. 2 is a transverse vertical sectional view 15 substantially on the plane of line 2—2 of Fig. 1; and

Fig. 3 is a diagrammatic view of the three overlapping webs.

In certain circumstances it is desirable to combine two or more webs of flexible material with 20 their edges in overlapped relation and to wind the combined product ready for use in subsequent operations. The example here given of such material, is paper and Cellophane. In the present instance there are two rolls of paper 16 and 11 and a roll of transparent Cellophane 12 which it is desired to combine with their edges 25 in overlapped relation, the Cellophane being the center section of the combined webs. The winding machine employed may be of any conventional type, such as the well-known "center wind" 30 machine. Such a machine may consist essentially of a rotatable supporting roll 13 on which rests winding shaft 14 conveniently carried by two arms 15 that are pivotally supported on 35 shaft 16. It will be seen that, by this expedient, the winding shaft is displaced automatically as wound material accumulates thereon in a well understood manner. Suitable means for driving the parts are provided and here take the following form: mounted on power shaft 17 is a 40 driving pinion 18 that meshes with a gear 19 on supporting roll 13. At the other end of supporting roll 13 is a gear 20 that drives gear 21 mounted on shaft 16 which latter carries another 45 gear 22 meshing with intermediate pinion 23 on arm 15 and meshing, in turn, with gear 24 on winding shaft 14. Webs 25, 26 and 27 from rolls 10, 11 and 12 are led over suitable guide rolls 50 such as 28, 29 and 30 to supporting roll 13 and around the latter to winding shaft 14. As will be particularly plain from Fig. 3, webs 25, 26 and 27 are guided into slightly overlapped relation at their longitudinal edges and are wound on the winding shaft in this relation. In the 55 overlapped section or zone of web 27 is a body of

adhesive, and this may obviously be applied at any time either before web 27 is made into roll 12 or during the passage of the web from said roll 12 to the winding shaft. This adhesive may be of any suitable character such as glue or latex, 5 but it must be responsive to the application of heat. In the present instance, the adhesive is applied to web 27 in the overlapping zones as said web passes around supporting roll 13. Preferably there is employed a fountain 31 containing a body of adhesive 32 in which latter is pivotally immersed a fountain roll 33 that transfers the adhesive to transfer rollers or wheels 34 bearing on overlapping edges of web 27. The fountain roll may conveniently be driven from supporting roll 13 by means of gears 35, 36 and 37. It will be noted that, at the point where the adhesive is applied, web 27 is outermost and the adhesive is applied on the exposed surface of said web 27 in the overlapping zones, and it will 10 now be understood that when said web 27 reaches the winding shaft it will adhere to the previously wound portion of webs 25 and 26. Bearing against the upper side of the wound material are heating elements 38 and 39, one for each overlapping zone of the webs, by the action of which the uniting of the webs is completed. The heating elements may be of any suitable construction but are preferably designed as follows: carried 15 by arms 15 are extensions 40 supporting, at their free ends, a shaft 41. Pivotally carried by shaft 41 are supporting members 42 that extend rearwardly toward pivotal support 16 of arms 15, and mounted on supporting members 42 are the T-shape heating elements. The heating elements 20 may be heated in any suitable manner, but preferably an electric current is used, binding posts 43 being utilized to receive suitable wire connections. The large dotted circle 44 in Fig. 2 represents the roll of wound material near the completion of the winding operation, and above it 25 is seen in dotted lines 38a the position of the heating elements at that time. It will be observed that owing to the double pivot action around 16 and 41 the angular position of the 30 heating element is changed but slightly during the progress of the winding operation.

45 indicates a handle by means of which arms 15 and the rewind shaft may be lifted, and a pawl and ratchet mechanism is indicated at 46 50 and 47 by means of which the winding shaft may be held in elevated position.

I claim:

1. A machine of the character set forth including: a winding shaft displaceable as the 55

- wound material increases thereon; guide means to lead two webs of flexible material in overlapped relation to said winding shaft, one of said webs carrying on its overlapping section a body of adhesive responsive to heat; a heating element to engage the wound material in the zone of the body of adhesive; and supporting means for said heating element responsive to an increase in diameter of the wound material.
- 5 3. A machine of the character set forth including: a rotatable supporting roll; a winding shaft resting on said supporting roll; pivotally sup-

ported arms carrying the winding shaft and permitting the latter to recede from the supporting roll in response to an increase in diameter of the wound material on the winding shaft; a heating element, to engage the wound material, pivotally supported at the free end of the arms and extending backwardly toward the pivotal support for the arms; and guide means to lead two webs in overlapped relation around the supporting roll to the winding shaft.
